DESIGN FOR A JACKET

Isidore Love, New York, N. Y.

Application November 9, 1942, Serial No. 108,719

Term of patent 3½ years

To all whom it may concern:

Be it known that I, Isidore Love, a citizen of the United States of America, residing in New York city, county of New York and State of New York, have invented a new, original, and ornamental Design for a Jacket, of which the following is a specification, reference being had to the accompanying drawing, forming part thereof,

Fig. 1 is a front view of a jacket showing my new design.

Fig. 2 is a rear view thereof.

I claim:

The ornamental design for a jacket, substantially as shown.

ISIDORE LOVE,
